(57) **CLAIM**

The ornamental design for a cover for cable management raceway, as shown and described.

DESCRIPTION

FIG. 1 is a perspective view of a front side of the design for a cover for cable management raceway in accordance with a preferred embodiment of the present invention;

FIG. 2 is a front view of the cover for cable management raceway of FIG. 1;

FIG. 3 is a left view of the cover for cable management raceway of FIG. 1;

FIG. 4 is a right view of the cover for cable management raceway of FIG. 1;

FIG. 5 is a top view of the cover for cable management raceway of FIG. 1;

FIG. 6 is a bottom view of the cover for cable management raceway of FIG. 1; and,

FIG. 7 is a rear view of the cover for cable management raceway of FIG. 1.

Portions of the design shown in broken lines form no part of the claimed design.
